UNITED STATES PATENT OFFICE.

AUGUSTIN GAGNE, OF CENTRAL FALLS, RHODE ISLAND, ASSIGNOR TO HEMPHILL COMPANY, OF PAWTUCKET, RHODE ISLAND, A CORPORATION OF MASSACHUSETTS.

MACHINE FOR KNITTING SPLIT FABRIC.

Application filed June 28, 1921. Serial No. 481,144.

This invention relates to knitting machines for producing split fabric but more particularly to circular automatic knitting machines adapted to knit split foot hosiery

- 5 and an object of the invention is to provide simple automatic mechanism capable of being operated at high speed with a minimum of strain and wear upon the needles and their knitting butts.
- 10 In order that the principles of the invention may be readily understood I have shown merely as an example an illustrated embodiment hereinafter fully set forth while the scope of the invention will be more particularly pointed out in the appended claims.

In the drawings:

Fig. 1 is a front elevation of a circular knitting machine embodying the invention;

20 Fig. 1^a is a transverse section on a reduced scale taken through the needle cylinder just above the needle butts to show the relative length of the needle butts;

Fig. 2 is a plan view of the machine;

25 Fig. 3 is a front elevation of the knitting head of the machine;

Fig. 4 is a plan section taken on the line 4—4 of Fig. 1;

30 Fig. 5 is a detail vertical section through the central portion of the secondary knitting cams and through the latch ring showing the two sets of yarn guides and the yarn cutters mounted therebetween, the needle cylinder being shown in dotted lines;

Fig. 6 is a detail side elevation of the cutters and yarn clamps for the primary and secondary threads, the cutters in this figure being shown closed;

35 Fig. 7 is a view similar to Fig. 6 showing the cutters and yarn clamps open;

40 Fig. 8 is an outside elevation of the secondary cam block, its supporting means, and correlated parts, the needle cylinder being shown in dotted lines;

Fig. 9 is an inside elevation of the second-45 ary cam set and associated parts;

Fig. 10 is a diagram of the various cams for actuating the needles, said cams occupying their proper positions for circular knitting;

50 Fig. 11 is a view similar to Fig. 10 illustrating the various cams in positions preparatory to knitting either the heel or the toe pocket of a stocking;

Fig. 12 is also a diagram of the various 55 needle operating cams similar to Figs. 10

and 11, the cams in said figure being arranged for knitting the split fabric of the foot and with the cylinder moving in the forward direction;

Fig. 13 is a diagram of said cams showing the same in substantially the same positions as in Fig. 12 but with the cylinder moving in the reverse direction;

Fig. 14 is a diagram on a greatly enlarged scale of two sections of fabric produced by the machine of this invention and wherein opposite adjacent edges of said two sections are united by interknitted loops of the respective sections; and

Fig. 15 is a side elevation of a stocking 70 foot illustrating a sample of the work adapted to be performed upon said machine.

The knitting machine herein employed as an exemplification of the invention, substantially embodies the characteristics of the 75 type of machine known as the "Banner" machine and fully disclosed in the U. S. patent to Hemphill No. 933,443 patented September 7, 1909. This machine has the usual

frame 1 within which is mounted a needle cylinder 2 preferably, although not essentially revoluble, and a non-revoluble cam carrier 3 having an annular portion or ledge

4. Mounted in the main frame 1 is a main shaft 5 carrying suitable pulleys 6, 7 and 8 80 respectively employed as quick speed, slow speed and loose pulleys. A pattern shaft 9 is mounted in said frame and has thereon an appropriate pattern drum 10. Upon said

pattern drum is a peripheral rib or cam 11 which engages with a follower 13 carried by a pivoted clutch shifting lever 14 connected with and for throwing the usual clutch from reciprocating to rotary driving

instrumentalities and vice versa, said latter 90 instrumentalities being well known features of said Hemphill patent and for further information concerning the same reference may be had thereto.

The follower 13 is arranged to travel 100 through cross slots 12, 12 from one side of said rib 11 to the other so as to effect the shifting of said clutch member.

By means of the mechanism just described the needle cylinder 2 is adapted to be given 105 at certain times in the knitting operation a continuous rotary movement as for example during the knitting of the leg of the stocking while at other times said cylinder is given a to and fro or reciprocating movement 110

during the knitting of the heel and toe pocket of the stocking and in the present example this reciprocating or to and fro movement is utilized to knit the split fabric of the foot and although the present embodiment of the invention has been described as having a revolving needle cylinder and stationary cams, obviously within the spirit and scope of the invention, the same is not limited to this construction.

The cam plate 3 has provision for a limited vertical movement, the same being mounted upon the usual cam slide 15 mounted for vertical movement in said frame 1 and carrying at its lower portion cam followers 16, 17 and 18 adapted to engage ribs upon a cam 19 mounted upon and to turn with the pattern shaft 9, said cam being adapted to move said cam plate up or down to vary the length of the loops during the knitting of the leg and other portions of a stocking. A latch ring 20 is pivoted at one side of the machine upon an upright post 21, and at an angle of approximately 90° from said post said latch ring engages and is supported by an upright post or standard 22, substantially as in said Hemphill patent.

The latch ring 20 is connected with the post 21 by a pivot pin 23 and yieldingly engaging the under side of said latch ring is a spring actuated foot 24 mounted in said post 21 and adapted to exert a yielding upward action against said latch ring which, under normal conditions, is locked in its operative position against the standard 22 by a latch 25 which engages a pin 26 upon said latch ring.

The needles shown in the present embodiment are of the latch needle type and are arranged in a circular series of a number consistent with the diameter of the work to be performed upon a machine. These needles are divided into two substantially equal series, one series having what are known as long knitting butts while the other series has the usual short knitting butts, said long butt needles being so-called "instep" needles are adapted to be withdrawn, preferably elevated, at times in the operation of the machine by the usual instep cams 27 and 28 (see Figs. 1, 3, 4 and 10 to 13 inclusive). These cams are mounted upon a slide 29 (see Figs. 1, 3 and 4) arranged to slide vertically in a standard 30 secured to the cam plate 3, appropriate movement being imparted to said slide by a bell crank lever 31 pivoted at 32 to a portion of the standard 30, one arm of said lever being connected with said slide 29 while the other arm is connected at 33 with a link 34 extending to and having connection at 35 with the upper end of the clutch shifting lever 14, these connections being such that when said clutch lever is in the position for rotary knitting the cams 27 and 28 will be in their lower-

most or depressed positions and when said lever 14 is in a position to effect to and fro or reciprocating knitting, said cams 27 and 28 will automatically be moved to the upper positions and thereby effect the withdrawal of the instep or long butt needles whose butts are arranged to engage said cam 27 and be elevated thereby, said cam 27 being far enough from the face of the needle cylinder to engage only the long butts permitting the short butts to pass without interference. The cam 28, however, is placed close up to the cylinder so as to engage either long or short butts which happen to be in their elevated positions when said cam 28 and the cam 27 are depressed.

Mounted upon the cam plate 3 with the instep cams is a cam block 36 (see particularly Figs. 3 and 4) arranged to slide laterally with respect to said needle cylinder between angle plates 37 disposed at opposite sides of said block and secured to the cam plate 3. A spring 38 is interposed between said cam block and a suitable fixed abutment 39 and constitutes means yieldingly 90 to maintain said cam block in its operative position with respect to the needle cylinder. The cam block 36 herein constitutes the support for what are termed the primary knitting cams of the machine consisting of the usual stitch cams 40, 41 (see particularly Figs. 4 and 10 to 13 inclusive), a lower central guide cam 42 and an upper central guide member 43. The inner faces of the cams 40, 41, 42 and 43 are concaved and lie normally in the plane coinciding with the outer face of the needle cylinder 2, said cams being withdrawn from this position only when it is desired to level the needles for transferring or when it is desired to withdraw said cams to get at the needles of the cylinder for the purpose of withdrawing or replacing needles. The usual means employed in the Banner machine for either manually or automatically retracting the cam block 36 for the purposes just described may be and herein are employed, said means consisting of a hand lever 44 pivoted at 45 to the standard 22, said lever being connected by a link 46 with the cam block 36. 110 To automatically retract said cam block, the means herein shown consist of a link 47 extending from one arm of said lever 45 downwardly to and into engagement with a cam lever 48 arranged to cooperate with a suitable rib 49 upon the face of the pattern drum 10. The withdrawing of said cam block 36 also serves to rock the latch 25 which has an end engaging the rear end of said cam block and disconnects said latch 125 from the pin 26 permitting the latch ring to be moved upwardly by the spring foot 24 shown in Fig. 8.

The cam block 36 is also provided with a pair of narrowing pickers 50, 50 pivoted 130

upon said block in a manner characteristic of said Banner machine and arranged to operate in the usual manner. The latch ring 20 is also provided with the usual supply of yarn levers 51 herein five, hereinafter referred to as the primary yarn guides (see Figs. 2 and 5) said yarn levers being operated in the usual manner from the pattern drum 10. Also supported upon said latch 10 ring is a supporting arm 52 for the usual yarn clamping and cutting devices 53 and 54 respectively for the primary yarns (see Figs. 2, 5, 6 and 7), said yarn clamp and cutter being operated by an operating lever 15 55 pivoted at 56 to said arm 52, said lever being operatively connected with the pattern shaft to operate automatically with the changing of the yarns.

The needle cylinder is provided with the usual web holder bed 57 surmounted by the web holder cam ring 58 of the usual Banner construction having lugs 59 to engage the latch ring 20 (see Fig. 8) so as to effect relative movement between said cap ring and the 25 sinker bed ring all of which parts, being operable in the usual manner, require no further description.

The parts hereinbefore described, as has been stated, are common to the Banner type 30 of knitting machine and these parts are operated automatically from the pattern shaft 9 by pattern mechanism generally indicated by the numeral 60 (see Fig. 1).

An object of the invention, as hereinbefore stated, is to provide a machine for knitting split fabric and in carrying out this part of the invention in a very simple and efficient manner, a secondary set of knitting cams has been provided which is indicated 40 generally at 61 (see Figs. 4, 9, 10, 11, 12 and 13). This set of knitting cams preferably includes a pair of stitch cams 62, 63, a lower guide cam 64 an upper guide cam 65 and a guard cam 66 for said upper guide cam. 45 The inner faces of said several cams are concaved and are arranged normally to lie in a plane substantially coinciding with the plane of the outer face of the needle cylinder, which plane also coincides with the 50 plane of the inner faces of the cams of said primary set.

Appropriate supporting instrumentalities are provided for said secondary knitting cams to maintain said secondary knitting cams in substantially the same horizontal plane as are the primary knitting cams whereupon certain needles including those with long knitting butts will be actuated during the knitting of certain parts of the 60 stocking or at substantially the same time that other needles including the regular short butt needles are acted upon as herein-after more fully set forth.

It is desirable that said secondary cams be 65 adjustable vertically with respect to the pri-

mary cams in order to provide perfect alignment between the two and in order to carry out this feature of the invention, said secondary cams are mounted in a manner hereinafter described upon a plate 67 which, in turn, is attached to a slide 68 adjustably arranged to move vertically in a bracket 69, the latter being secured to the frame 1 by means of screws 70, 70. The bracket 69 is substantially in the form of a channel with 75 in which the slide 68 moves and means, herein screws 71, extend through slots in said bracket into screw-threaded engagement with said slide and for the purpose of fixing said slide in its predetermined adjusted relation with said bracket. Means are provided to move said slide relatively to the bracket including a screw 72 having screw-threaded engagement with a laterally projecting portion 73 of said bracket arranged 80 beneath said slide and in its adjusted position said screw 72 is secured by a check nut 74 (see particularly Figs. 3, 5, 8 and 9).

It is desirable at certain times to move the secondary knitting cams radially of the needle cylinder to withdraw them to positions where they will not act upon needle butts and one of the occasions when such a movement of the cam is desired is when the needles are to be levelled for transferring, while 85 at certain other times such as, for example, when the needles may have become caught or will have to be replaced by hand, such a movement of said cams is also desirable. As a means for accomplishing this result the 90 stitch cams 62 and 63 and a lower guide cam 64 are mounted upon a cam block 75 (see Figs. 4, 5 and 9), said block being arranged to slide upon the plate 67 between angle brackets 76, said cam block being yieldingly 95 maintained in its operative position by springs 77 interposed between said cam block and an abutment or bracket 78. It is desirable that the cam block 75 be capable 100 of manual as well as automatic retraction. Hence it is left free to be retracted at will 105 by the operator while the means for automatically retracting said cam block are preferably arranged to retract said block simultaneously with the retraction of the primary 110 cam block.

For automatically retracting the cam block 75, a lever 79 is pivoted at 80 to the under side of a plate 67 (see Figs. 1, 3, 8 and 9), one end of which lever is adapted 115 to engage the side nearest to the needle cylinder of a pin 81 depending from the under side of the cam block 75, (see Fig. 5) said pin being arranged to work within a slot formed in said plate 67.

The opposite end of the lever 79 is connected by means of a link 82 with an arm 83 attached to the link 46 hereinbefore referred to as constituting a part of the means for retracting said primary cam block. 120

- There are occasions during the operation of the machine when it is desired to retract the upper guide cam 65 from its operative position independently of the cams 62 and 63. Said upper guide cam 65 is moved out for heel and toe work. Therefore said cam 65 is shown slidably mounted preferably in the cam block 75, said cam having a slide 84 (see Figs. 4, 5 and 9) arranged to slide 10 in a suitable groove in the top of said cam block, it being held within said groove herein by a plate 85 (see Figs. 4 and 5). This cam 65 is preferably so mounted that it may be withdrawn either manually or automatically and for withdrawing said cam automatically means have been provided including an operating lever 86 (see particularly Figs. 4 and 9) said lever being pivoted at 87 to a stationary part of the cam support. 15 The lever 86 may receive its motion from any appropriate source but herein means are provided upon the pattern drum 10 which include a rib 88 arranged to engage a cam lever 89 to rock the same about its pivot 90. 20 The lever 89 imparts its movement in one direction viz, when the same is raised by the cam 88 to said cam lever 86 to retract the cam 65 and means operatively connect said lever 86 with the lever 89 including a connecting rod 91 which is pivotally connected at one end with said lever 89 and at its opposite end with an arm 92 secured to one end of a rock shaft 93, the latter being arranged to rock in appropriate bearings in 25 the machine. To the opposite end of said rock shaft an arm 94 is secured which, in turn, is connected by means of a rod 95 with one end of the lever 86. The cam 65 is yieldingly maintained in its operative position by appropriate means such, for example, as a spring 96 connected at one end to the connecting rod 91 and at its opposite end to a fixed portion of the machine frame, this spring tending at all times to maintain 30 the operative end of the cam lever 89 in contact with the periphery of the pattern cam or drum.
- Obviously when an auxiliary or secondary set of cams is employed, means must also be provided to feed yarn to the needles that are actuated by said secondary cam. Hence a secondary yarn guide 97 (see Figs. 2, 3 and 5) has been provided upon the latch ring 20 in a position appropriate to said secondary knitting cam, herein substantially diametrically opposite to the primary knitting cams. The secondary yarn guide 97 is in the form of a lever pivoted at 98 to said latch ring, the free end of which is arranged to move in a suitable slot 99 formed therein. 35 The purpose of the secondary cams, as previously stated, is principally to function the needles during the knitting of split fabric and where the formation of such fabric 40 is, as in the present type of machine, limited to a certain portion of the knitted article as, for example, the foot, the secondary yarn guide 97 must be moved into and out of its operative position when said secondary cams 70 are moved into and out of their operative position. Preferably, therefore, said yarn guide is arranged to operate automatically with the cam 65 which controls the operations of said secondary cams and, as a convenient method of effecting cooperation between said members, said yarn guide 97 is provided with an extension 100 having a cam surface 101 along its under edge arranged to be engaged by a lever 102 (see Figs. 2, 4, 5 and 8). This lever is herein shown pivoted at 103 to the bracket 78 and has a lateral projection 104 extending underneath the extension 100 of the yarn guide. 75 The lower end of said lever 102 is connected through a link 105 with a lever 86. Hence any movement of said lever 86 to move the cam 65, will effect a similar movement of the yarn guide 97; that is if the cam 65 is retracted from its operative position, the yarn guide 97 will be raised to its inoperative position and vice versa. 80
- To insure the proper engagement of the long butts of the needle with the cam 65, the guard cam 66 is mounted directly above said cam 65 with cam surfaces 66' at opposite ends thereof to cause a deflection of the needle butts provided they are too high to strike said cam 65 and this cam 66 is likewise supported upon the bracket 78 herein by means of a rod 106 (see particularly Figs. 4 and 5) said rod extending rearwardly from said cam 66 into engagement with said bracket within which it is secured by screws 107. 85
- The usual widening pickers 108, 109 common to the Banner type of knitting machine are mounted herein upon the bracket 78 with their operative ends capable of cooperation with the cams 62 and 63 (see particularly Figs. 4, 9 and 10 to 13 inclusive). These pickers are pivotally mounted upon said bracket 78 and means preferably of the usual type are provided for holding said pickers in their inoperative positions when narrowing and widening operations are not to be performed. In the present example these means include a stop plate 110 (see Figs. 4, 5 and 9) that is arranged to engage the arms of said pickers 108 and 109 and to depress said arms. To control said stop plate, means are shown including a bracket 111 to which said plate is attached, said bracket being mounted at the upper end of a rod 112 vertically movable in the bracket 67. The lower end of said rod 112 is operatively connected with a lever 113 (see Figs. 1 and 8) pivoted at 114 to the under side of the frame 1 and having connection through a link 115 and a cam lever 116 with the cam 90
- 110
- 115
- 120
- 125
- 130

surfaces 117 formed upon the cam 19 (see particularly Fig. 1).

To facilitate feeding and withdrawing the secondary yarn to and from the work a yarn holder and cutters have been provided for said secondary yarn in addition to those previously described for use in connection with the primary yarn guides, said holder and cutters consisting of a movable member 118 (see Figs. 5, 6 and 7) suitably mounted upon the supporting arm 52 and adjustably connected with the free end of the cutter operating lever 55.

The member 118 has a notch 119 in its outer edge near the lower end thereof in proximity to the base member 120 of the supporting arm 52 within which to receive the yarn leading from the secondary yarn guide 97 after said guide has been raised and the needle cylinder rotated a portion of a rotation. The movable member 118 is arranged to move between two plates 121 and 122, said plates being yieldingly pressed against said movable member by a suitable spring herein the spring 123 (see Fig. 5).

The lower end of the plate 121 is slightly bevelled to form a cutting edge 124 which is arranged to cooperate with a similar cutting edge 125 formed upon the lower side of the notch 119. Hence when said movable member 118 is moved upwardly and the cutting edge 124 passes the cutting edge 125, any yarn which has, by reason of the movement of the needle cylinder, passed into said notch, will be severed by said cutting edge.

The lower end 126 of the plate 122 is arranged substantially on a level with the cutting edge 124 so that, when the movable member passes upwardly between said plates, said end 126 will extend below the notched portion of the movable member and this plate being yieldingly held against said cutter, the yarn will be clinched or bound between said plate and the movable member without severing, and sufficiently to hold the end of the yarn so that when the yarn guide is again moved into operative position, the end of the yarn held by said members will not pass into the fabric but will be held until the needles have received sufficient yarn to form the initial loops.

Arranged at the back of the needle cylinder between the primary and secondary cams is a switch cam 127 of usual construction and arranged to engage only the long knitting butts and then only when the needle cylinder is travelling in a reverse direction whereupon the said butts will be moved upwardly to the idle level and for the purposes hereinafter set forth. When the butts of the needles are passing in the opposite direction, that is forwardly and along the usual channel for circular knitting, the long butt needles will engage said switch cam and throw the same up without changing the

positions of said needles. To this end the cam 127 is provided with a shaft 128 (see Fig. 4) pivotally mounted in a fixed bracket 129 and having a spring 130 for normally holding said switch cam in the positions shown in Figs. 10 to 13 inclusive.

The operation of the knitting machine hereinbefore specifically described in general is the same as in the usual automatic Banner stocking machine and therefore needs no further explanation. The operation of the parts embodying the novel features of the invention are, however, as follows:

Referring particularly to Fig. 10 and assuming that circular knitting is to be produced, the needle cylinder moves in the direction of the arrow in said figure, causing all of the needles to travel along the path indicated by the dotted lines at A, both long and short butts passing over the stitch cam 41 of the primary knitting cams, under the guide cam 43 and stitch cam 40 to form the usual knitting wave.

After leaving the cam 41 the needles are raised by an incline 131 on the annular ledge 4 to the normal level A along which all of the needles pass until they strike the first stitch cam 62 of the secondary set, this cam being arranged to depress all of the needles below the yarn receiving position so that neither the long or the short butt needles will take yarn at this time, said needles being again raised to their normal level by the incline 132. As the long butt needles pass the switch cam 127, said cam will be raised to the dotted position shown in Fig. 10, and the short butt needles being too short to engage said cam will not interfere at all with the same.

While the last circular course prior to the formation of the high splice or heel pocket is being knitted, the mechanism hereinbefore described is set into operation to change from rotary to reciprocatory knitting and simultaneously to raise the instep cam 27 to its upper position (see Fig. 11) but the needle cylinder is not reversed until all of the long butt needles B have passed said instep cam and been elevated thereby, Fig. 11 showing the arrangement of the long butt needles B and the short butt needles C immediately prior to the first reverse movement of the needle cylinder, the direction of which is indicated by the arrow in said Fig. 11.

The next step in the operation of forming the stocking will, for the sake of convenience, be assumed to be the formation of the narrowing and widening for the heel pocket and at this time the long butt needles, indicated at B in their upper position are not brought into operation. Therefore it is desirable that the cam 65 be withdrawn so that said long butt needles may pass along the

idle level as shown at B without interruption, the means for operating said cam 65 being hereinbefore described.

Continued reciprocating movements of the needle cylinder result in the gradual raising of the leading short butt needles by means of the narrowing pickers 50 until the desired number of courses have been knitted, whereupon the widening pickers 10 which, up to this time have been held out of action by the means described, are released and return those needles previously raised by the narrowing pickers in reverse order to their operative positions, thus effecting 15 the gradual increase in the length of courses forming the heel pocket. Upon the completion of the heel pocket, the split foot fabric is then produced.

Assuming the parts to be in positions 20 shown in Fig. 11 with the machine having completed its last reciprocating movement to complete the heel pocket and with the needle cylinder just about to start on its reverse movement as shown by the arrow in said 25 Fig. 11, the cam 65 being at this time returned to its operative position, the first short butt needle D passes along to the first narrowing picker 50 and is raised to the idle or upper level of the long butt needles B and 30 is thereby prevented from receiving yarn from the primary yarn guide. The needle cylinder, during reciprocating movements, makes approximately a rotation; hence said elevated short butt needle D, together with 35 all of the long butt needles B, will pass into engagement with the cam 65 and will be caused to pass below said cam and below the stitch cam 62, thus receiving yarn from the secondary yarn guide and casting the same 40 to form loops.

Referring now to Fig. 12 and assuming all of the cams herein to be in the positions similar to those of the cams in Fig. 11, with the needle cylinder having already started on its 45 next forward movement (that is in the direction of the arrow shown in Fig. 12) the needle E, which is the short butt needle at the opposite end of the short butt series from the needle D, being now the first needle in 50 the short butt series, engages the narrowing picker resting normally against the top of the stitch cam 41 and is elevated by said picker to the upper level which thereby constitutes the last needle of the long butt series 55 B. The needles of this series B which travel along the upper level, engage the cam 65 and are depressed thereby and beneath the secondary stitch cam 63 causing all of the needles thereof to take yarn and from stitches, including the short butt needle E. After passing 60 the cam 63, the long butt needles pass along the incline 132 and over the instep cam 27 back to the upper level but, by reason of the fact that the cam 27 is away from the 65 face of the needle cylinder, the needle E

which has a short butt, passes up the incline 132 and then along the top of the annular portion 4 which is the normal level for the short butt needles, thus joining the needles of said short butt series. This needle, however, does not move far enough to again engage the picker on this particular movement of the needle cylinder and as the needle cylinder reverses before such can take place, consequently said needle E will, upon the 70 return movement, pass through the primary knitting cams and take its yarn in the usual manner interknitting the loop formed of the regular yarn with that previously formed from the secondary yarn, thus uniting the 80 fabric formed upon the long butt needles which is formed from said secondary yarn, with the fabric formed upon the primary needles to which the primary yarn is advanced in the usual manner. 85

Upon the next reverse movement of the cylinder as shown in Fig. 13, the needle D will again be raised by the narrowing picker 50 of the primary set to the upper position and will pass over the primary knitting cams 90 and through the secondary set of cams, thus taking yarn from said secondary yarn guide and casting its loop. The long butt needles B, after passing through the secondary set of cams in the direction of the arrow shown 95 in Fig. 13, will be raised to their upper idle level by means of the switch cam 127 but the needle D, not having a long butt, and in view of the fact that said cam 127 is placed at a distance from the needle cylinder 2, and 100 can be engaged only by the long butts, will pass along the normal level of the needles of the course C and thence through the primary knitting cams and receive a second yarn which is interknit with the yarn received 105 from the secondary cams, thus repeating the operations previously described.

When the split fabric has been completed the next step is preferably to form a toe pocket which is effected by withdrawing the 110 cam 65 and permitting the instep needles of the series B merely to idle along the upper level and the needles of the short butt series C to pass through the primary cams and be picked up in their usual order for narrowing and finally picked down by the widening pickers until the narrowing and widening courses have been completed. 115

Following these operations the usual operations of the Banner machine may be carried out and as the various threads are inserted and withdrawn, they will be gripped and cut by the cutters provided therefor and hereinbefore specifically described. 120

In Fig. 14 I have illustrated in abbreviated form and greatly enlarged a section of the split fabric produced during the aforesaid operations, the parts shown being that portion of the fabric which constitutes the sole and instep portions of the foot and if 125 130

desired the high splice and front ankle portion.

In said Fig. 14 the sole and instep portions are marked 131 and 133 respectively, 5 only two needle wales 132, 132 of the section 131 and four needle wales 134, 134 of section 133 being shown, these sections being united herein by single needle wales 135 and 136 at opposite edges of the section 131. By 10 reason of the peculiar operation of the needles during the knitting operation, the terminal needles of the primary series from which the section 131 is formed produces double strand loops 138 one strand of which 15 forms a complete loop 139 while the other strand forms a partial loop 140, both of said strands crossing strands of a single loop 137 which is interknitted with the double loop 138 and forms the terminal loop of the 20 fabric section 133. Although said loop 137 is knitted upon the same needle that forms the double loop 138, the loops 137 and 138 of the wale 136 are knitted upon the end or suture needle D forming the suture seam at one 25 side of the section 131 while the loops 137' and 138' at the opposite side of the section 131 are knitted upon the needle E, said needles D and E forming the terminal needles of the short butt series C.

30 The loops 139 and 140 are tied to their respective fabric sections by lateral strands at the closed and the throat portions of the loop 139 respectively by the yarn 141 of the loop 149 and the strand 146 which tend to 35 maintain their respective loops in proper alignment with respect to each other and with the other wales of said sections. The loop 137, however, is a single strand loop owing to the fact that the terminal needles, 40 in producing said loops from secondary yarn, are not picked up, as when knitting from primary yarn, previous to their passing through the secondary cams. Therefore said single loop 137 will be connected by 45 means of a lateral strand 142 with a preceding loop in the same course and by an oblique strand 144 with the first loop 145 of a subsequent course and it will be understood that the construction of the loops of 50 the suture wale 136 will be substantially identical with the loops of the suture wale 135 except that the double loops of the section 131 in said wale 136 will constitute the terminal loop of a course having at its opposite end a single loop 137 of the wale 135.

55 In Fig. 15 I have shown the foot of a stocking adapted to be constructed upon the machine hereinbefore described, said figure showing the relative locations of a heel pocket 147, sole 148, toe 149, and in certain cases a high splice 150, all formed of primary yarn in accordance with the section 131 of Fig. 14 while the instep 151 and the front ankle portion 152 may be considered 60 as embodying the construction of the fabric

section 133. The two sections 131 and 133 are shown united by the suture seam 135 extending from the top of the high splice to the toe pocket.

70 While I have herein shown and described certain embodiments of my invention and have disclosed and discussed in detail the construction and arrangement incidental to such disclosure it is distinctly to be understood that the invention is limited neither to the mere details or relative arrangement of parts nor to the specific applications herein shown but that extensive variations may be made without departing from the principles thereof.

80

I claim:

1. In a circular knitting machine the combination with a single needle cylinder provided with long and short butt needles respectively arranged in wholly consecutive 85 series and including terminal suture needles of the same length butts as those of one of said series, the said needles all being of substantially the same length, of primary and secondary sets of knitting cams arranged at 90 substantially the same level about said single needle cylinder, the inner faces of the cams of both sets being normally disposed in a circular plane substantially coinciding with the outer face of said needle cylinder. 95

2. In a circular knitting machine the combination with a needle cylinder provided with long and short butt needles and including terminal suture needles of the same length butts as those of one of said series, of 100 primary and secondary sets of knitting cams arranged at substantially the same level, the inner faces of the cams of both sets being normally disposed in a circular plane substantially coinciding with the outer face 105 of said needle cylinder, the stitch cams of said secondary set being arranged to prevent all of said needles from taking yarn during continuous circular knitting.

3. In a circular knitting machine, the combination with a needle cylinder provided with long and short butt needles and including terminal suture needles of the same length butts as those of one of said series, of primary and secondary sets of cams including stitch cams mounted substantially at the same level, the inner faces of the cams of both sets being normally disposed in a circular plane substantially coinciding with the outer face of said needle cylinder, said secondary set of cams including a central guide cam, means for elevating the long butt needles for reciprocating knitting, and means to retract said central guide cam only for narrowing and widening. 110 115

4. In a circular knitting machine, the combination with a needle cylinder provided with long and short butt needles and including terminal suture needles of the same length butts as those of one of said series, 120 125 130

of primary knitting cams to function both long and short butt needles during rotary knitting, secondary knitting cams adapted to act upon both long and short butt needles

- 5 during rotary knitting to prevent said needles taking yarn, means to separate the long butt needles from the short butt needles, a central guide cam to guide one set of needles into engagement with the secondary cams, and means to retract only said central guide cam for and during heel and toe knitting.

5. In a circular hosiery knitting machine, the combination with a needle cylinder carrying long and short butt groups of needles and including terminal suture needles of the same length butts as those of one of said series, of primary knitting cams to function both long and short butt needles 15 during rotary knitting and the short butt needles only during reciprocating knitting, secondary knitting cams to function said long butt needles during reciprocating knitting simultaneously with the functioning of said short butt needles by said primary cams, the stitch cams of said secondary knitting cams having portions for preventing all of the needles from taking secondary yarn during rotary knitting and for preventing the short butt group of needles 20 from taking secondary yarn during reciprocating knitting.

6. In a hosiery knitting machine the combination with a needle cylinder having long and short butt needles and including terminal suture needles of the same length butts as those of one of said series, of primary knitting cams to function all of said needles during rotary knitting, means to withdraw said long butt needles, secondary knitting cams including an independently retractible central guide cam and a pair of stitch cams, means to retract said central guide cam for the formation of the heel and toe, said central guide cam being adapted to guide said long butt needles into engagement with said secondary stitch cams to effect the formation of loops upon said long butt needles simultaneously with the formation 40 of loops upon said short butt needles by said primary knitting cams, and means operable when said long butt needles are withdrawn to move the leading needles of the short butt series into positions to be 45 functioned by said secondary knitting cams to unite the strips formed respectively upon said long and short butt needles.

7. In a circular hosiery knitting machine, the combination with a needle cylinder provided with long and short butt needles and including terminal suture needles of the same length butts as those of one of said series, of primary and secondary sets of knitting cams, mounted substantially at the 60 same level and with their inner faces nor-

mally disposed in a circular plane substantially coinciding with the outer face of said needle cylinder, said primary knitting cams being arranged to function both long and short butt needles during rotary knitting, 70 said secondary knitting cams including stitch cams provided with bevelled outer faces to prevent needles passing thereby from taking the secondary yarn, and means to restore said needles to their normal levels 75 after passing said secondary stitch cams.

8. In a circular hosiery knitting machine, the combination with a needle cylinder provided with long and short butt needles and including terminal suture needles of the same length butts as those of one of said series, of a primary set of knitting cams to function both long and short butt needles during rotary knitting and short butt needles only during reciprocating knitting, 80 a secondary set of knitting cams to function the long butt needles simultaneously with the functioning of said short butt needles by, said primary knitting cams during reciprocating knitting to form split fabric, said 85 secondary knitting cams including an independently retracting central guide cam, means to retract said central guide cam to permit said long butt needles to remain idle during the formation of heel and toe 90 pockets, means for independently retracting the knitting cams of said secondary set, and means simultaneously to retract said central guide cam and said secondary stitch cams 95 preparatory to the transferring operations. 100

9. A split work knitting machine comprising, in combination, a series of long butt needles and a series of short butt needles, suture needles having the same length butts as those of one of said series, all of said 105 needles being of substantially the same length and carried by a single needle cylinder, primary knitting cams to function one of said series of needles to form a web, a secondary knitting cams to function the 110 other of said series of needles to form a web, and means to effect knitting upon the terminal needles of the short butt series only alternately by said primary and said secondary knitting cams to unite said webs. 115

10. A knitting machine comprising a series of long butt needles, a series of short butt needles, a set of knitting cams to function one of said series of needles, a second set of knitting cams to function the other 120 series of needles, and means to effect the formation of two loops upon the terminal needles of said short butt series automatically to each single loop upon the terminal needles of said long butt needles to unite 125 the fabrics formed respectively upon said long butt needles and said short butt needles.

11. A knitting machine comprising a series of long butt needles, a series of short butt needles and including terminal suture 130

- needles of the same length butts as those of one of said series, primary and secondary sets of knitting cams to function respectively said long and short butt needles during reciprocating knitting, and means including narrowing pickers to effect cooperation between the terminal needles of the short butt series only, alternately with said primary and said secondary sets of knitting cams.
12. In a knitting machine, the combination with a series of long butt and a series of short butt needles together constituting a complete circle of needles and including terminal suture needles of the same length butts as those of one of said series, of means to withdraw predetermined of said needles, and means to function said withdrawn needles including a set of knitting cams arranged with their inner faces substantially in contact with the stems of said needles, substantially throughout the knitting operations.
13. In a knitting machine, the combination with a series of long butt and a series of short butt needles together constituting a complete circle of needles, and including terminal suture needles of the same length butts as those of one of said series, of means to elevate said long butt needles and the terminal needles of the short butt series, and a set of knitting cams for functioning said elevated needles only.
14. In a knitting machine, the combination of a needle carrier having a series of long butt and a series of short butt needles together constituting a complete circle of needles and including terminal suture needles of the same length butts as those of one of said series, primary and secondary knitting cam sets, said needle carrier and said cam sets being arranged for relative rotary and reciprocating movements, the inner faces of the cams of both of said sets being normally substantially in the same circular plane, means to withdraw predetermined of said needles for reciprocating knitting, means to effect cooperation between the withdrawn needles and said secondary cams and the remaining needles and said primary cams to knit separate webs, and means to effect cooperation between the terminal needles of one of said sets alternately with said primary and secondary cams to form suture seams uniting the edges of said webs.
15. In a knitting machine a series of long butt needles and a series of short butt needles respectively arranged in wholly consecutive sets together constituting, with suture needles having the same length butt as those of the short butt series, a complete circle of needles, knitting cams to function all of said needles in rotary knitting and one length of butts only in reciprocating knitting, and a secondary set of knitting cams adapted to form loops upon the other length of butts during reciprocating knitting, the stitch cams of said secondary knitting set being capable of depressing the remaining needles of the series below the secondary yarn receiving points to prevent them from taking said secondary yarn.
16. In a knitting machine an uninterrupted series of long butt needles, an uninterrupted series of short butt needles, together constituting an entire circle of needles and including terminal suture needles whose butts are of the same length as those of one of said series, a main set of cams, and a secondary set of knitting cams the latter including an independently retractible guide cam central with respect to said secondary set.
17. In a machine for knitting split foot hosiery, a secondary set of knitting cams including a retractible central guide cam, and means independently to withdraw said central guide cam independently of the stitch cams of said set, for the formation of the heel and toe.
18. In a knitting machine, a secondary set of knitting cams, including a guide cam centrally positioned with respect to said set of cams, means to withdraw all of said cams from engagement with the needles, and means to retract said central guide cam independently of the remainder of said secondary set of knitting cams.
19. In a machine for knitting split fabric, a secondary set of knitting cams, including a guide cam centrally positioned with respect to said set of cams, arranged to remain normally in operative positions, means to withdraw all of said cams from operative positions preparatory to transferring, and means to withdraw said central guide cam from operative position for narrowing and widening independently of the remaining cams of said secondary set of knitting cams.
20. In a knitting machine a secondary set of knitting cams including a guide cam centrally positioned with respect to said set of cams, a block for carrying said cams, means for raising and lowering said block, means to withdraw said cams from operative positions, and means to retract said central guide cam independently of the remaining cams of said secondary set of knitting cams.
21. In a knitting machine a secondary set of knitting cams including a central guide cam, a guard cam for said central guide cam, and means independently to retract said central guide cam with respect to said guard cam and the stitch cams of said set.
22. In a machine for knitting split foot hosiery, a secondary set of knitting cams including two stitch cams, and a central guide cam, a carrier block for said stitch cams and upon which said central guide cam is arranged to slide, means for raising and lowering said carrier block including a plate, a guard cam carried by said plate, widening

pickers carried by said plate, means normally to retain said pickers in inoperative positions, means independently to retract said central guide cams, and means automatically to effect cooperation between said widening pickers and said guard cam to widen.

23. In a knitting machine an uninterrupted series of long butt needles, an uninterrupted series of short butt needles together constituting an entire circle of needles, a main set of cams, and a secondary set of knitting cams including a guide cam central with respect to the cams of said secondary set and arranged normally in operative position, means to retract said central guide cam independently of the remaining cams of said secondary set of knitting cams, and secondary yarn feeding means operable in conjunction with said central guide cam.

24. In a knitting machine, a secondary set of knitting cams including a central guide cam arranged normally in operative position, means to retract said central guide cam independently of the remaining cams of said secondary set of knitting cams, a secondary yarn feed, and means operatively connecting said secondary yarn feed with said central guide cam to effect co-operative action therebetween.

25. A knitting machine comprising, in combination, a series of long and short butt needles, a primary knitting cam set, and a secondary knitting cam set, the latter having a guide cam central with respect thereto, the inner faces of the cams of both of said sets being adapted normally to lie in the same circular plane, means automatically to withdraw both of said sets for transferring, and means to retract the central guide cam of said secondary cam set independently of the remaining cams of said secondary knitting cam set preparatory to forming the heel and toe pockets of a stocking.

26. In a knitting machine, the combination with a series of needles having long and short knitting butts, of means to elevate said long butt needles, narrowing pickers to elevate the terminal needles of the short butt series during reciprocating knitting, and a set of knitting cams including a retractible guide cam central with respect to said set of knitting cams and adapted to function said elevated needles to form split fabric and to be withdrawn from operation during narrowing and widening independently of the remaining cams of said secondary set of knitting cams.

27. A circular knitting machine comprising a series of long butt needles, a series of short butt needles, a set of knitting cams to function one of said series of needles, a second set of knitting cams to function the other series of needles, and means including

two yarn guides substantially diametrically opposed to each other, to effect the formation of two loops in a course in a single wale upon each of the two terminal needles of said short butt series automatically to each single loop upon the two terminal needles of the long butt needles in the same wale, to unite the fabrics formed respectively upon said long butt needles and said short butt needles.

28. A circular knitting machine comprising a rotary needle cylinder having a series of consecutive long butt needles, a series of consecutive short butt needles, said series together constituting the complete circle of needles, a set of knitting cams to function one of said series of needles, a second set of knitting cams to function the other series of needles, and means to effect the formation of two loops upon the terminal needles of said short butt series automatically to each single loop upon the terminal needles of said long butt needles to unite the fabrics formed respectively upon said long butt needles and said short butt needles.

29. A circular split work knitting machine comprising in combination, a single needle cylinder having a circle of needles all of substantially the same length and made up of a series of consecutive long butt needles and a series of consecutive short butt needles including suture needles having the same length butts as those of one of said series and at substantially the same position on the needles, primary knitting cams to function one of said series of needles to form a web, secondary knitting cams to function the other of said series of needles to form a web, and means including two yarn guides substantially diametrically opposed to each other to effect knitting upon the terminal needles of the short butt series only alternately by said primary and said secondary knitting cams to unite said webs.

30. That method of knitting split fabric which consists in knitting reciprocatingly upon two series of needles to form two fabric sections united into a tubular fabric by spaced suture seams composed wholly of double strand loops knitted from one yarn upon the terminal needles of one of said series and of single loops interknitted with said double strand loops in the same wale.

31. That method of knitting split fabric which includes the simultaneous knitting upon two series of needles, with different yarns, in reversing the movement of the needles and causing the now leading needle of one of said series to receive yarn from its respective feed without casting its loop and to take yarn from the yarn feed of the other series and casting the loops of its own yarn over said newly acquired yarn, thereby interknitting a double terminal loop with a sin-

gle terminal loop and thereby forming a suture seam wholly composed of double and single loops alternated in successive courses.

32. That method of knitting split fabric which includes the alternate knitting in opposite directions upon two series of needles and with different yarns, the terminal needles of one of said sets being actuated to take yarn from a common yarn feed as tail needles and when passing said yarn feed as leading needles merely to wrap yarn therefrom about their shanks without knitting and subsequently in the same course to receive yarn from the yarn feed of the other series of needles to effect the interknitting of a double strand terminal loop of one yarn with a single strand terminal loop of the other yarn and thereby forming a suture seam wholly composed of double and single loops alternated in successive courses.

33. That method of knitting split fabric which consists in knitting reciprocatingly upon at least two series of needles with different yarns to form two sections of fabric and during said knitting operations in causing each terminal needle of one series to operate first as the tail needle of its series receiving the yarn of its series and casting its loop, then upon a reverse movement operating as the leading needle of its own series for the purpose of receiving yarn but without casting its loop, and subsequently in the same movement receiving yarn from the yarn feed of the other series and in drawing the same through the two loops suspended from said needle thereby forming alternate double and single loops from different yarn but in the same wale and thereby forming a suture seam wholly composed of double and single loops alternated in successive courses.

34. A circular, hosiery, fashioning, split work, knitting machine having a circular series of needles composed of two sets having contrasting length butts for cooperating with the knitting cams and including terminal suture needles having butts of the same length as those of one of said sets, a main set of knitting cams, an auxiliary set of knitting cams, and yarn feeds cooperating with said sets of cams, and an instep cam movable into and out of action and controlling the instep needles at the fashioning operation, and also controlling one set of needles at the auxiliary set of cams.

35. A circular, hosiery, fashioning, split work, knitting machine having a circular series of needles composed of two sets having contrasting length butts for cooperating with the knitting cams and including terminal suture needles having butts of the same length as those of one of said sets, a main set of knitting cams, an auxiliary set of knitting cams, and yarn feeds cooperating with said sets of cams, an instep cam, and means to move the same into function-

ing position to move instep needles out of action for the fashioning operation and to move said instep cam into functioning position at the commencement of split work to direct needles at the auxiliary set of cams.

36. That method of knitting split fabric which consists in knitting reciprocatingly with a primary yarn and a secondary yarn respectively upon two series of needles to form double strand suture needle loops from one of said yarns only upon the terminal needles only of one of said series and then in forming single strand suture loops only in the next course upon the terminal needles in the same wale and in interknitting said double strand loops with said single strand loops of said other yarn in the same wale.

37. That method of knitting split fabric which consists in knitting reciprocatingly with a primary yarn and a secondary yarn respectively upon two series of needles to form double strand suture needle loops from one of said yarns only upon the terminal needles only of one of said series and then in forming single strand suture loops only in the next course upon the terminal needles in the same wale and in interknitting said double strand loops with said single strand needle loops of said other yarn formed upon the same terminal needles.

38. That method of knitting split fabric which consists in knitting reciprocatingly with a primary yarn and a secondary yarn respectively upon two series of needles to form double strand suture needle loops upon the terminal needles only of one of said series and then in forming single strand suture loops only in the next course upon the terminal needles in the same wale and in interknitting said double strand loops with said single strand needle loops of said secondary yarn in the same wale.

39. That method of knitting split fabric which includes the simultaneous knitting upon two series of needles, in reversing the movement of the needles and causing the now leading needle of one of said series to receive yarn from its respective feed without casting its loop and to take yarn from the yarn feed of the other series and casting the loop of its own yarn over said newly acquired yarn, thereby to form double strand suture needle loops from one of said yarns only upon the terminal needles only of one of said series, and to form single strand suture loops only in the next course upon said terminal needles, interknitting a double terminal needle suture loop of one of said yarns with a single terminal needle suture loop of the other of said yarns.

40. That method of knitting split fabric which includes the alternate knitting in opposite directions upon two series of needles, the terminal needles of one of said sets being actuated to take one of said yarns from

a common yarn feed as tail needles and when passing said yarn feed as leading needles merely to wrap yarn therefrom about their shanks without knitting and subsequently in the same course to receive the other yarn from the yarn feed of the other series of needles to form double strand suture needle loops from one of said yarns only upon the terminal needles only of one of said 10 series, and to form single strand suture loops only in the next course upon said terminal needles to effect the interknitting of a double strand terminal needle loop of one of said yarns with a single strand terminal 15 needle loop of the other yarn.

41. That method of knitting split fabric which consists in knitting reciprocatingly upon at least two series of needles with two different yarns to form two sections of fabric and during said knitting operations in causing each terminal needle of one series to operate first as the tail needle of its series receiving the yarn of its series and casting its loop, then upon a reverse movement operating as the leading needle of its own series for the purpose of receiving yarn but without casting its loop, and subsequently in the same movement receiving yarn from the yarn feed of the other series and in drawing 30 the same through the two loops suspended from said needle, thereby forming alternate double suture needle loops and single suture needle loops from said two yarns respectively but in the same wale whereby said 35 wale is composed in alternate courses of double loops and single loops.

42. Mechanism for knitting split fabric comprising two series of needles arranged in a circular set, a primary set of knitting cams, a secondary set of knitting cams, means to introduce a primary yarn and means to introduce a secondary yarn at said 40 cam sets respectively, and means cooperating with said parts to form double strand suture needle loops upon the terminal needles only of one of said series and to form in alternation therewith single strand suture needle loops only of said secondary yarn in said wales respectively, whereby each suture wale 45 is wholly composed in successive courses of double strand needle loops and single strand needle loops.

43. Mechanism for knitting split fabric comprising two series of needles arranged in a circular set, a primary set of knitting cams, a secondary set of knitting cams, means to introduce a primary yarn and means to introduce a secondary yarn at said 55 cam sets respectively, and means cooperating with said parts relatively to move the needles and the cams in reverse directions and to cause the leading needle of one of said series to receive yarn from its respective feed without casting its loop and to 60 take yarn from the yarn feed of the other 65

series and to cast the loops of its own yarn over said newly acquired yarn, whereby each suture wale is wholly composed in successive courses of double strand needle loops and single strand needle loops, which double 70 and single loops are respectively interknit- 75 ed with each other, so as wholly to make up each suture seam.

44. Mechanism for knitting split fabric comprising two series of needles arranged in a circular set, a primary set of knitting cams, a secondary set of knitting cams, means to introduce a primary yarn and means to introduce a secondary yarn at said cam sets respectively, and means cooperat- 80 ing with said parts alternately to recipro- 85 cate the needles in opposite directions relatively to said cams and to cause the terminal needles of one of said series to be actuated to take one of said yarns as tail needles and when passing said yarn as leading needles merely to wrap yarn therefrom about their shanks without knitting and subsequently in the same course to receive said other yarn and to form double strand 90 suture needle loops upon the terminal needles only of one of said series and to form in alternation therewith single strand suture 95 needle loops only of said secondary yarn in said wales respectively, whereby each suture 100 wale is wholly composed in successive courses of double strand needle loops and single strand needle loops.

45. Mechanism for knitting split fabric comprising two series of needles arranged in a circular set, a primary set of knitting cams, a secondary set of knitting cams, means to introduce a primary yarn and means to introduce a secondary yarn at said cam sets respectively, and means co-operat- 105 ing with said parts to reciprocate said needles and in so doing to cause each terminal needle of one series to operate first as the tail needle of its series receiving the yarn of its series and to cast its loop and upon a reverse movement operating as the leading needle of its own series to receive yarn without casting its loop, and subsequently in the same movement receiving yarn from the 110 yarn feed of the other series and to draw the same through the two loops suspended from said needle, and to form double strand suture needle loops upon the terminal needles only of one of said series and to form in alternation therewith single strand suture 115 needle loops only of said secondary yarn in said wales respectively, whereby each suture wale is wholly composed in successive courses of double strand needle loops and single strand needle loops, and picker means 120 cooperating with said needles at the primary and secondary sets of cams to cause the formation of suture seams.

46. A circular, split work, knitting ma- 125 chine having a single needle cylinder carry- 130

ing a circular series of needles composed of two sets only of needles, said two sets having contrasting length butts for cooperation with the knitting cams, all of the needles of each set being alike and one of said sets including terminal suture needles having the same length butts as those of the needles of the set wherein said suture needles are included and at the same position on the 10 needles, and two sets of knitting cams and yarn feeds for cooperation with said needles.

47. A circular, split work, knitting machine having a circular series of needles composed of two sets only of needles, said 15 two sets having contrasting length butts for cooperation with the knitting cams, all of the needles of each set being alike and one of said sets including terminal suture needles having the same length butts as 20 those of the needles of the set wherein said suture needles are included and at the same position on the needles, and two sets of knitting cams and yarn feeds for cooperation with said needles, and means cooper- 25 ating with said parts to effect the joining of two split work fabric sections by suture seams.

48. A circular, split work, knitting machine having a circular series of needles composed of two sets only of needles, said two 30 sets having contrasting length butts for cooperation with the knitting cams, all of the needles of each set being alike and one of said sets including terminal suture needles 35 having the same length butts as those of the needles of the set wherein said suture needles are included and at the same position on the needles, and two sets of knitting cams and yarn feeds for cooperation with 40 said needles, and picker means to effect the operation of said suture needles in the formation of the suture seams.

49. A circular, split work, knitting machine having a circular series of needles composed of two sets only of needles, said two 45 sets having contrasting formations for cooperation with the knitting cams, all of the needles of each set being alike and one of said sets including among said like needles 50 terminal suture needles, and two sets of knitting cams and yarn feeds for cooperation with said needles, and picker means to effect the operation of said suture needles in the formation of the suture seams composed 55 wholly of single strand needle loops and double strand needle loops in alternation in the same wale.

50. A split work, hosiery, knitting machine comprising in combination a circular 60 series of needles arranged in two sets only, said two sets having contrasting length butts for cooperation with the knitting cams, all of the needles of each set being alike and one of said sets including terminal suture 65 needles having the same length butts as

those of the needles of the set wherein said suture needles are included, a primary set of knitting cams with its yarn feed, a secondary set of knitting cams with its yarn feed, said two sets of knitting cams being 70 at substantially the same level, and picker means at both sets of knitting cams to effect the cooperation of said suture needles at both knitting cams in the formation of suture 75 seams thereat.

51. A split work, hosiery, knitting machine comprising in combination, a circular series of needles all of substantially the same length and arranged in two sets, a primary set of knitting cams with its yarn 80 feed and a secondary set of knitting cams with its yarn feed, a single needle cylinder for all of said needles, the inner faces of both sets of said cams being in substantially the same circumferential plane as the outer face 85 of the needle cylinder and at substantially the same level.

52. A split work, hosiery, knitting machine comprising in combination, a circular series of needles arranged in two sets, a primary set of knitting cams with its yarn feed and a secondary set of knitting cams with its yarn feed the secondary set of knitting cams being movable radially as an entirety 90 but occupying its normal inner position during split work, and means to guide one set of the needles out of the path of the secondary set of knitting cams during split work.

53. A split work, hosiery, knitting machine comprising in combination, a circular series of needles arranged in two sets, a primary set of knitting cams with its yarn feed and a secondary set of knitting cams with its yarn feed, a block supporting said secondary set of knitting cams, and means for effecting in and out adjustment of said cam block manually and automatically, said secondary set of knitting cams occupying its normal inner position during split work, 100 and means to guide one set of the needles out of the path of the secondary set of knitting cams during split work.

54. A split work, hosiery, knitting machine comprising in combination, a circular 115 series of needles arranged in two sets, a primary set of knitting cams with its yarn feed and a secondary set of knitting cams with its yarn feed, the said secondary set of cams including an upper guide cam 65 120 movable radially independently of the remainder of the said secondary set of cams.

55. A split work, hosiery knitting machine comprising in combination, a circular series of needles arranged in two sets, a primary 125 set of knitting cams with its yarn feed and a secondary set of knitting cams with its yarn feed, the secondary set of cams including a guide cam 65 and operative connections between the primary set of cams and said 130

guide cam 65 of the secondary set, whereby said primary cams and said guide cam 65 may be moved simultaneously into and out of position said guide cam being so moved independently of movement of the remaining cams of the said secondary set.

56. A split work, hosiery knitting machine comprising in combination, a circular series of needles arranged in two sets, a primary set of knitting cams with its yarn feed and a secondary set of knitting cams with its yarn feed, the secondary set of cams including a guide cam 65 and operative connections between the primary set of cams and said guide cam 65 of the secondary set, whereby said primary cams and said guide cam 65 may be moved simultaneously into and out of position said guide cam being so moved independently of movement of the remaining cams of the said secondary set, and pattern means for governing said movement of the primary set of cams and the guide cam 65.

57. A split work, hosiery knitting machine comprising in combination, a circular series of needles arranged in two sets only, said two sets having contrasting length butts for co-operation with the knitting cams, all of the needles of each set being alike, and one of said sets including terminal suture needles having the same size butts as those of the needles of the set wherein said suture needles are included, a primary set of knitting cams with its yarn feed, a secondary set of knitting cams with its yarn feed, said two sets of knitting cams being at substantially the same level, and means for relatively reciprocating the needles and said cams whereby two split work fabric sections united by suture seams are produced.

58. A split work, hosiery knitting machine comprising in combination, a circular series of needles arranged in two sets, a primary set of knitting cams with its yarn feed and a secondary set of knitting cams with its yarn feed, narrowing and widening means for forming heel and toe pockets, the secondary set of cams including a guide cam, and means for effecting withdrawal of said guide cam at substantially the commencement of fashioning said guide cam being so moved independently of movement of the remaining cams of the said secondary set, so that idle needles may pass along the idle level without knitting.

59. A split work, hosiery knitting machine comprising in combination, a circular series of needles arranged in two sets, a primary set of knitting cams with its yarn feed and a secondary set of knitting cams with its yarn feed, said needles including long butt instep needles and short butt heel and toe needles, the secondary set of cams including a guide cam, and means for automatically withdrawing the same at substantially the commencement of fashioning said guide cam being so moved independently of movement of the remaining cams of the said secondary set, whereby the idle long butt needles may pass in a straight line along the idle level without knitting.

60. A split work, hosiery knitting machine comprising in combination, a circular series of needles arranged in two sets, a primary set of knitting cams with its yarn feed and a secondary set of knitting cams with its yarn feed, said needles including long butt instep needles and short butt heel and toe needles, the secondary set of cams including a guide cam, and means for automatically withdrawing the same at substantially the commencement of fashioning said guide cam being so moved independently of movement of the remaining cams of the said secondary set, whereby the idle long butt needles may pass in a straight line along the idle level without knitting.

61. A split work, hosiery knitting machine comprising in combination, a circular series of needles arranged in two sets, a primary set of knitting cams with its yarn feed and a secondary set of knitting cams with its yarn feed, said needles including long butt instep needles and short butt heel and toe needles, the secondary set of cams including a guide cam, and means for automatically withdrawing the same at substantially the commencement of fashioning said guide cam being so moved independently of movement of the remaining cams of the said secondary set, whereby the idle long butt needles may pass in a straight line along the idle level without knitting, and means to return said cam 65 to fashioning position at the completion of fashioning.

62. A split work, hosiery knitting machine comprising in combination, a circular series of needles arranged in two sets, a primary set of knitting cams with its yarn feed and a secondary set of knitting cams with its yarn feed, said needles being short butt needles and long butt needles respectively, and the terminal needles of one of said sets acting as suture needles and having the same length butts as those of the set in which it is included, and means relatively to reciprocate the needles and the cam sets and periodically to elevate selected needles and to cause on the first stroke of split work the first elevated short butt needle, functioning as the last of the series of elevated needles, to take yarn from the secondary yarn guide at the secondary set of cams.

63. A split work, hosiery knitting machine comprising in combination, a circular series of needles arranged in two sets, a primary set of knitting cams with its yarn feed and a secondary set of knitting cams with its yarn feed, said needles being short butt needles and long butt needles respectively, and the terminal needles of one of said sets acting as suture needles and having the same length butts as those of the set in which it is included, and means relatively to reciprocate the needles and the cam sets and periodically to elevate selected needles and to cause on the first stroke of split work the first elevated short butt needle, functioning as the last of the series of elevated needles, to take yarn from the secondary yarn guide at the secondary set of cams, the said needles being arranged in two continuous or uninterrupted series as long butt and short butt needles.

64. A split work, hosiery knitting machine having a circular series of needles composed of continuously arranged long

butt needles and continuously arranged short butt needles, a primary set of knitting cams and its yarn feed, and a secondary set of knitting cams and its yarn feed, and means cooperating with said parts to cause the short butt needles to knit at the primary knitting cams and the long butt needles to knit at the secondary cams, but to cause the two end short butt needles, i. e., one at each end of the series of short butt needles, to knit on the long butt side alternately at the respective ends of the long butt needles.

64. A split work, hosiery knitting machine having a circular series of needles composed of continuously arranged long butt needles and continuously arranged short butt needles, a primary set of knitting cams and its yarn feed, and a secondary set of knitting cams and its yarn feed, and means cooperating with said parts to cause the short butt needles to knit at the primary knitting cams and the long butt needles to knit at the secondary cams, but to cause the two end short butt needles, i. e., one at each end of the series of short butt needles, to knit on the long butt side alternately at the respective ends of the long butt needles, and to cause each suture seam to be wholly composed in alternate courses of single strand needle loops and double strand needle loops.

65. A split work, hosiery knitting machine having a circular series of needles composed of continuously arranged long butt needles and continuously arranged short butt needles, a primary set of knitting cams and its yarn feed, and a secondary set of knitting cams and its yarn feed, and means cooperating with said parts to cause the short butt needles to knit at the secondary cams, but to cause the two end short butt needles, i. e., at the two ends of the short butt series of needles, to knit alternately with both threads, namely, first at the auxiliary side of the machine with the long butt needles and then with the short butt needles at the primary side of the machine, thus making suture seams at both sides.

66. In a knitting machine, a secondary set of knitting cams including a central guide cam, a guard cam for said central guide cam having an overhanging portion at each side thereof to guide needles to said central guide cam, and means to withdraw said central guide cam relatively to said guard cam, and independently of the remaining cams of said secondary set of knitting cams, to effect engagement thereof only with the long butt needles.

67. In a knitting machine, a circular series of knitting needles including short and long knitting butts arranged respectively in separate groups, primary and secondary knitting cams to function said long and short butts respectively during the formation of split fabric, a single movable element including

instep cams to effect the engagement of the short and long knitting butts respectively with the primary and secondary knitting cams, and means rendered operative by the segregation of said long and short butt needles to cause the leading short butt needles to pass the primary cams without knitting and to knit at the secondary cams.

68. In a machine for knitting split fabric, a series of needles consisting of separated groups of short and long knitting butts, one of said groups having its terminal needles of equal butt length acting as suture needles, primary knitting cams to function all of the needles in rotary knitting, secondary knitting cams, an instep cam adapted to segregate the short and long butt groups of needles to be operated respectively by said primary and secondary knitting cams during the formation of split fabric, and picker means to elevate the leading short butt needle at each movement in reciprocating knitting to cause said leading needles to pass the primary knitting cams without knitting but to effect the winding of the yarn about the shanks of said leading needles.

69. In a knitting machine, the combination of a series of knitting needles including two separate groups respectively provided exclusively with short and long knitting butts, the terminal needles of the short butt series acting as suture needles, primary and secondary sets of knitting cams arranged in the same horizontal plane and with their inner faces lying normally in a common cylindrical plane, an instep cam and a switch cam arranged respectively upon opposite sides of said secondary cams to elevate the long butt needles after passing through said secondary cams to a plane above the primary knitting cams, means to depress the short butt needles below the knitting plane of said secondary knitting cams, and picker means adapted to raise the leading needle of the short butt series of needles to the level of said long butt needles as they pass said primary knitting cams to prevent said leading needle from knitting at the primary cams.

70. In a machine for knitting split fabric a series of knitting needles divided into two groups of short and long butts respectively, the terminal needles of the short butt series acting as suture needles, a set of secondary knitting cams including relatively fixed stitch cams and a relatively movable central guide cam arranged to engage the long butt needles close up to their shanks during split fabric knitting, said stitch cams having needle deflecting surfaces for depressing all of the needles below said secondary cams in rotary knitting and for depressing only the short butt needles below said secondary knitting cams during reciprocating knitting.

71. In a machine for knitting split fabric, primary and secondary knitting cams ar-

- ranged in substantially the same horizontal plane and with their inner faces lying normally in a common cylindrical plane in combination with a circular series of needles in 5 two sets, all the needles being of substantially the same length and having all their butts at substantially the same level, including the end needles of one of said sets which constitute suture needles.
- 10 72. A circular, hosiery, fashioning, split work, knitting machine having a circular series of needles composed of two sets having contrasting formations for cooperating with the knitting cams, a main set of knitting 15 cams, an auxiliary set of knitting cams and yarn feeds cooperating with said sets of cams, an instep cam movable up into action and down out of action, and means to move said cam up into action at the commencement 20 of fashioning so as to render the instep needles idle, and means to move said instep cam up into action at the commencement of split work, so as to cause one set of needles to pass the auxiliary set of cams so as not 25 to knit thereat.
73. A circular, hosiery, fashioning, split work, knitting machine having a circular series of needles composed of two sets having contrasting formations for cooperating 30 with the knitting cams and yarn feeds cooperating with said sets of cams, an instep cam movable up into action and down out of action, and means to move said cam up into action at the commencement of fashioning so as to render the instep needles idle, and means to move said instep cam up into action at the commencement of split work, so as to cause one set of needles to pass the auxiliary set of cams so as not to knit there- 35 at, and means to move said instep cam down out of action to cause said last mentioned set of needles to knit at the auxiliary set of cams.
74. A circular knitting machine comprising 40 in combination, a needle carrier a set of long butt needles, and a set of short butt needles whose terminal needles act as suture needles and a cam carrier; means relatively to rotate said parts to produce rotary work on the said needles, means active at the end of rotary work to divide the said circle of needles for reciprocating knitting into two groups having butts at a higher level and a lower level respectively, means to introduce 45 distinct yarns at spaced points, means relatively to reciprocate the needle carrier and cam carrier and to cause on successive strokes of such reciprocation one group of needles to knit at one yarn and the other 50 group to knit at the other yarn and the loops of the two series to be interengaged as suture seams formed upon said terminal short butt needles.
75. A circular knitting machine comprising 55 in combination, a needle carrier a set of long butt needles, and a set of short butt needles whose terminal needles act as suture needles and a cam carrier, means relatively to rotate said parts to produce rotary work on the said needles, means active at the end of rotary work to divide the said circle of needles for reciprocating knitting into two groups having butts at a higher level and a lower level respectively, means to introduce 60 distinct yarns at spaced points, means relatively to reciprocate the needle carrier and cam carrier and to cause on successive strokes of such reciprocation one group of needles to knit at one yarn and the other group to knit at the other yarn and the loops of the two series to be interengaged as suture seams formed upon said terminal short butt needles.
76. A circular knitting machine comprising, in combination, a needle carrier and a cam carrier, said needle carrier having a circle of needles comprising consecutive long butts and consecutive short butts, thus providing two series from which two groups may be formed the terminal needles of the short butt series acting as suture needles, means relatively to rotate said parts to produce rotary work on the needles, means to divide the needles for reciprocating knitting into two groups of which the terminal short butt needles may be changed from one group to the other group, means to introduce distinct 75 yarns at spaced points, means relatively to reciprocate the needle carrier and cam carrier, means to cause on each of a series of successive strokes of such reciprocation one group of needles to knit at one yarn and the other group to knit at the other yarn and the loops of the two series to be interengaged as suture seams formed upon said terminal short butt needles.
77. A circular knitting machine comprising, in combination, a needle carrier and a cam carrier having a circle of needles comprising consecutive long butts and consecutive short butts, thus providing two series from which two groups may be formed, the terminal needles of the short butt series acting as suture needles, means to rotate said needle carrier to produce rotary work on the needles, means to reciprocate said needle carrier and to introduce distinct yarns at spaced points and to cause needles to knit at both yarns on each reciprocation of said needle carrier, means to divide the needles into two groups for said reciprocating knitting, of which the terminal short butt needles may be changed from one group to the other group, means to cause on successive strokes of reciprocation of the needle carrier one group of needles to knit at one yarn and the other group to knit at the other yarn and the loops of the two series to be interengaged as suture seams formed upon said terminal short butt needles.
78. A circular knitting machine comprising, in combination, a needle carrier a set of long butt needles, and a set of short butt needles whose terminal needles act as suture needles and a cam carrier, means relatively to rotate said parts to produce rotary work on the said needles, means active at the end of rotary work to divide the said circle of needles for reciprocating knitting into two groups having butts at a higher level and a lower level respectively, means to introduce distinct yarns at spaced points, means relatively to reciprocate the needle carrier and cam carrier and to cause on successive strokes of such reciprocation one group of needles to knit at one yarn and the other group to knit at the other yarn and the loops of the two series to be interengaged as suture seams formed upon said terminal short butt needles.

the loops of the two series to be interengaged as suture seams formed upon said terminal short butt needles.

78. A knitting machine comprising in combination, a needle carrier and a cam carrier having a circle of needles comprising consecutive long butts and consecutive short butts, thus providing two series from which two groups may be formed, the terminal 10 needles of the short butt series acting as suture needles, means relatively to reciprocate said parts and to introduce distinct yarns at spaced points and to cause needles to knit at both yarns on each reciprocation, 15 said needles being in two series at different levels for knitting at said yarns respectively and thus forming split work, needle picker means acting to change terminal short butt needles temporarily from one level to the 20 other so as to act as suture needles at the new level.

79. A circular knitting machine for knitting split work, comprising a single needle cylinder with needle grooves, a cam carrier 25 surrounding the same and having its sets of knitting cams at substantially the same level, there being at spaced points about the needle

cylinder means to introduce distinct yarns for split work, a circular series of needles in said grooves, constituting two groups 30 composed respectively of short butt and long butt needles but all of substantially the same length, and of which the terminal short butt needles act as suture needles, said cam carrier having main and auxiliary sets of 35 knitting cams respectively functioning to present the needles of said two groups to said distinct yarns, said sets of knitting cams being at substantially the same distance from the needle cylinder, each set of 40 knitting cams including an advancing cam and a retracting cam both of which are close to the outer face of the needle cylinder, and both of which engage the needle butts in the grooves of the needle cylinder to reciprocate 45 them therein, means relatively to reciprocate the needle cylinder and the cam carrier so as to cause the needles to take said yarns at each reciprocation in the production of split work with interengaged loops forming suture seams.

In testimony whereof, I have signed my name to this specification.

AUGUSTIN GAGNÉ.
